GOVERNOR VALVE

James C. Weaver, Harrisburg, Pa., assignor to
Samuel Snyder, Harrisburg, Pa.

Application July 25, 1939, Serial No. 286,482

9 Claims. (Cl. 137—139)

My invention relates to new and useful improvements in automatic speed control means for automotive vehicles.

An important object of my invention is to provide a device for controlling and regulating the maximum speed of an automotive vehicle.

Another object of my invention is the provision of a device of the above-mentioned character that is automatic in its action to permit a greater quantity of fuel to be injected into the carburetor when the vehicle is rapidly accelerating below the maximum speed for which the device is set.

Still another object of my invention is the provision of a device of the above-mentioned character that will automatically permit a greater quantity of fuel to be injected into the carburetor when the vehicle is ascending an incline.

Yet another object of my invention is the provision of a device for controlling and regulating the speed of an automotive vehicle that may be effectively operated independently of the conventional throttle valve of the vehicle and that will in no way interfere with the actuation or operation of the same.

A further object of my invention is the provision of a device of the above-mentioned character that may be readily and expeditiously applied to vehicles already manufactured and in use.

A yet further object of my invention is the provision of a device of the above-mentioned character that is simple in construction and that is efficient and efficacious in the performance of its duties.

Other objects and advantages of my invention will be apparent during the course of the following description.

In the drawings, forming a part of this specification, and in which like numerals are employed to designate like parts throughout the same,

Figure 1 is a front elevation of my device, and showing the same associated with the fuel intake line of an automotive vehicle.

Figure 2 is a front elevation of my device, showing the front cover removed.

Figure 3 is a transverse sectional view, taken on the line 3—3 of Figure 2.

Figure 4 is a vertical sectional view, taken on the line 4—4 of Figure 2.

Figure 5 is a vertical sectional view, taken on the line 5—5 of Figure 2.

Figure 6 is a perspective view of a link member embodying a part of my invention, and

Figure 7 is a perspective view of another link member embodying a part of my invention.

In the accompanying drawings, wherein for

the purpose of illustration, is shown a preferred embodiment of my invention, the numeral 10 designates the carburetor of an automotive vehicle having the conventional gas feed line 11, throttle actuating lever 12 and throttle rod 13. The carburetor is formed with a lower flange 14 normally registerable with the flange 15 of the intake manifold 16 and which is adapted to be connected thereto by means of threaded bolts 23, or the like.

The numeral 17 designates a casing adapted to house the working parts embodying my invention. The casing includes a substantially cylindrical vertically disposed sleeve portion 18 having upper and lower peripheral flanges 19 and 20 adapted to register with the flanges 14 and 15 of the carburetor and intake manifold respectively. The flanges 19 and 20 are substantially diamond-shaped in plan and are provided adjacent the ends thereof with openings 21 and 22 adapted to align with openings in the flanges 14 and 15 to receive threaded bolts 23 which hold the same in close fitting engagement.

The casing is formed laterally of the sleeve portion 18 with a vertically disposed integrally connected supporting wall 24 which extends a substantial distance forwardly of the sleeve 18. The forwardly extending portion 25 of the wall 24 is provided with a transversely positioned web 26 which integrally connects the same with the sleeve. The wall 24 includes a peripheral flange 27 which defines a central horizontally disposed chamber 28 which is enlarged at the end 29 thereof to form a chamber 30 laterally of the sleeve 18. The forwardly extending portion 25 of the wall 24 is substantially circular in plan and the flange 27 defines an enlarged cupular chamber 31 the lower portion of which communicates directly with the central passage 28. The flange 27 is provided at spaced intervals therearound with lugs 32 having threaded recesses 33 therein adapted to register with the openings 34 in the front cover 35 and to receive the threaded bolts 36 which hold the cover securely in place.

The pintle 43 is positioned transversely of the vertical passage 37 of the sleeve 18 with the end 38 thereof journaled in the recess 39 formed in the inner wall of the passage and with the end 40 thereof extending through the sleeve 18 and into the chamber 30 to receive the lever arm 41. A throttle valve 42 is positioned within the passage 37 and is suitably fastened to the pintle 43.

The substantially disk-shaped pendulum or weight 44 is positioned in the chamber 31 and pendulously mounted on the boss 45 integrally

formed on the wall 24. The lower portion of the disk is stepped outwardly as at 46 to greatly increase the weight of the lower portion of the pendulum, and an abutment 47 is formed on its lower periphery to engage the stop member 48 preferably integrally formed on the inner periphery of the flange 27, as illustrated in Figure 2. The stop member 48 engages the abutment 47 to hold the weight slightly off center in the direction of the throttle valve 42 in order to normally assure the engagement of the abutment therewith, and the upper portion of the pendulum is provided with a plurality of arcuately spaced openings 49 to permit adjustment of the said pendulum relative to the stop 48.

The companion link members 50 and 51 are joined for longitudinal adjustment relative to each other, and the end 52 of the link 50 is pivotally connected to the pendulum adjacent the lower periphery thereof and at a point diametrically opposed to the middle opening 49. The end 53 of the link 51 is provided with spaced extensions 54 and 55 which slidably receive the pin 56 extending outwardly from the free end of the lever arm 41. The end 57 of the link member 50 is provided with an elongated slot 58 which slidably receives the pin 59 carried by the link 51 and the end 60 thereof is provided with a vertical slot 61 which receives the pin 56 of the lever arm 41 to securely hold the same between the extensions 54 and 55 of the link member 51.

When the device is interposed between the carburetor 10 and intake manifold 16, as illustrated in Figure 1, the throttle valve 42 may be positioned within the passage 37 to control the flow of fuel from the carburetor to the intake manifold; the throttle of the carburetor may be actuated in the conventional manner to control the flow of fuel therethrough. By adjusting the link members 50 and 51 relative to each other, the lever arm 41 may be acted upon to selectively position the throttle valve 42 for control of the vehicle at different predetermined speed limits. The heavy lower end of the pendulum 44 will assure the engagement of the abutment 47 with the stop 48 to normally hold the valve 42 in the selected position and to prevent an excess of gas from flowing through the passage 37 and into the intake manifold, thus effectively and efficaciously controlling and regulating the maximum speed of the vehicle.

When the vehicle is being rapidly accelerated, the inertia of the weighted pendulum 44 will cause the same to swing toward the throttle valve 42 and to move the same to a relatively open position, thus permitting a greater quantity of fuel to be injected by the carburetor into the intake manifold. When the forward impetus of the vehicle has been checked and the vehicle is traveling at an even rate of speed, the heavy lower portion of the pendulum will cause the abutment 47 to once more engage the stop member 48 for control of the vehicle. The pendulum will be similarly actuated when the vehicle is ascending an incline. The engine will require a greater quantity of gas and the pendulum will swing in the direction of the valve to open the same and to permit the carburetor to discharge a greater amount of fuel into the intake manifold. When the device is installed in the manner hereinabove described, the normal operation of the carburetor will be in no way interfered with, and the link members 50 and 51 may be adjusted relative to each other to position the throttle valve 42 in a manner to efficiently and effi-

ciously control and regulate the maximum forward speed of the vehicle.

It is to be understood that the form of my invention herewith shown and described, is to be taken as a preferred example of the same, and that various changes in the size, shape and arrangement of parts may be resorted to without departing from the spirit of my invention, or the scope of the appended claims.

Having thus described my invention, I claim:

1. In a valve construction, a casing having a passage; a valve plate mounted within said passage for regulating flow therethrough; a lever carried by the valve plate exteriorly of the said passage; weight means pendulously swingable within the casing; an adjustable coupling connecting the weight means and the said lever to permit the initial position of the valve plate to be regulated to permit a predetermined maximum flow to traverse the passage; and stop means engageable with but not connected to the weight to hold the same normally slightly off center to assure engagement therebetween and to prevent swinging of the weight in a direction to reduce the maximum flow through the passage, said weight having a plurality of arcuately spaced openings to permit adjustment of the same relative to the said stop means and being adapted to swing away from the stop means and in a direction to transiently increase the maximum flow through the passage when the casing is rapidly accelerated or inclined from the horizontal.

2. In a valve construction, a casing having a passage; adjustable flow control means disposed within said passage to regulate flow therethrough, an actuator arm carried by the said flow control means exteriorly of the said passage; weight means pendulously mounted within the casing; companion link members longitudinally adjustable relative to each other and pivotally connected to the weight means and to the said actuator arm, said link members being operative to initially position the flow control means to normally permit a selected maximum flow to traverse the passage; and stop means engageable with, but not connected to the weight means to prevent swinging of the weight in a direction to reduce the maximum flow through the passage, the said weight having provision for adjustment of the same relative to the stop means and being adapted to swing in a direction to increase the maximum flow through the passage when the casing is accelerated or tilted from the horizontal.

3. In a valve construction, a casing having a passage; a valve plate mounted within said passage for regulating flow therethrough; an actuator arm carried by the valve plate exteriorly of the said passage; weight means pendulously swingable within the casing; adjustable means pivotally connected to the weight and to the actuator arm to initially position the said valve plate to permit a maximum flow through the passage; and a stop means engageable with but not connected to the weight to prevent swinging of the same in a direction to reduce the maximum flow through the passage but permitting the same to swing in a direction to increase the maximum flow therethrough when the casing is rapidly accelerated or tilted from the horizontal.

4. In a valve construction, a casing having a passage; a valve plate mounted within said passage for regulating flow therethrough; weight means pendulously swingable within the casing

and operatively associated with the valve plate to initially position the same to normally permit a selected maximum flow through the passage; and a stop means engageable with but not connected to the weight to hold the same normally slightly off center to assure engagement therebetween and to prevent swinging of the said weight in a direction to reduce the maximum flow through the passage but permitting the same to swing in a direction to increase the maximum flow when the casing is accelerated or inclined from the horizontal.

5. In a valve construction, a casing having a passage; a valve plate mounted within said passage for regulating flow therethrough; a weight pendulously mounted in said casing; an actuator arm fixedly carried by said valve plate exteriorly of said passage; companion link members longitudinally adjustable relative to each other and pivotally connected to the weight and to the actuator arm, the said link members permitting the initial position of the valve plate to be regulated to normally permit a selected maximum flow to traverse the passage; and means to prevent swinging of the weight in a direction to reduce the maximum flow through the passage but permitting the same to swing in a direction to increase the maximum flow therethrough when the casing is accelerated or inclined from the horizontal.

6. In a valve construction, a casing having a passage; adjustable flow control means disposed within said passage for regulating flow therethrough; a weight pendulously mounted in said casing; an adjustable coupling connecting the weight and flow control means, said adjustable coupling permitting the initial position of the control means to be regulated to normally permit a selected maximum flow to traverse the passage; and stop means arranged forwardly of the weight, said stop means being engaged by but not connected to the weight to prevent swinging of the same in a direction to reduce the maximum flow through the passage but permitting the same to swing in a direction to increase the maximum flow therethrough.

7. In a valve construction, a casing having a passage; adjustable flow control means disposed within said passage for regulating flow therethrough; a weight pendulously mounted in said casing; an adjustable coupling connecting the weight and flow control means, said adjustable coupling permitting the initial position of the control means to be regulated to normally permit a selected maximum flow to traverse the passage; and means to prevent the said weight from swinging in a direction to reduce the maximum flow through the passage but permitting the same to swing in a direction to increase the maximum flow therethrough.

15 8. A valve comprising a casing having a passage; a pendulum mounted for swinging movement within said casing; a valve plate mounted within the passage of the said casing for regulating flow therethrough; adjustable means connecting the pendulum and the valve plate, said adjustable means permitting the initial position of the valve plate to be regulated to normally permit a predetermined maximum flow to traverse the passage; and a stop means cooperative with but not connected to the said pendulum for preventing swinging movement thereof in a direction to reduce the maximum flow through the passage but permitting the same to swing in a direction to increase the maximum flow therethrough.

20 9. A valve comprising a casing having a passage; a pendulum mounted for swinging movement within said casing; a valve plate mounted within the passage of the casing for regulating flow therethrough; adjustable means connecting the pendulum and the valve plate, said adjustable means permitting the initial position of the valve plate to be regulated to normally permit a selected maximum flow to traverse the passage; and means to prevent the said pendulum from swinging in a direction to reduce the maximum flow through the passage, but permitting the same to swing in a direction to increase the maximum flow therethrough.

30 JAMES C. WEAVER.
